Primary Examiner — Susan E Krakower

Assistant Examiner — Michelle M Reeves

(57) **CLAIM**

The ornamental design for a travel footrest, as shown and described.

DESCRIPTION

FIG. 1 is a front perspective view of a travel footrest design showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged detail view of area 9 shown in FIG. 1; and,

FIG. 10 is an enlarged detail view of area 10 shown in FIG. 2.

The broken lines in the drawings depict portions of the travel footrest that form no part of the claimed design.

The dot-dash broken lines in FIGS. 1 and 2 show the boundaries of the enlarged views of FIGS. 9 and 10 and form no part of the claimed design.

1 Claim, 10 Drawing Sheets
